UNITED STATES PATENT OFFICE.

AUGUST HOLSTE, OF BIELEFELD, GERMANY.

GARMENT.

No. 902,081.

Specification of Letters Patent.

Patented Oct. 27, 1908.

Application filed August 26, 1907. Serial No. 390,172.

To all whom it may concern:

Be it known that I, AUGUST HOLSTE, a subject of the King of Prussia, residing at Bielefeld, Prussia, in Germany, have invented 5 certain new and useful Improvements in Garments for Underwear, of which the following is a specification.

This invention relates to garments for underwear.

10 The underclothing of the known type, which entirely envelops the trunk or upper part of the body, has certain disadvantages, more particularly that of warming some parts of the body where heat is neither agreeable nor healthy. The parts which should 15 be kept warm are the abdomen and the back.

It has been previously proposed in surgical and orthopædic appliances and as a substitute for corsets to provide an abdominal 20 belt portion or covering detachably connected as by straps with a back or bust support or covering, but the object of the present invention is entirely different and relates essentially to an under garment or garments 25 for general wear which will be hereinafter described. These garments are made separate from each other, so that they can be 30 separately used, that is to say, one can be worn in the absence of the other, or one can be worn against the skin, for example on the abdomen, and the other can be simultaneously worn over another garment. This gives to the user greater control as to the 35 amount of clothing which can be worn at any given time. The connection between the garments is made by means of straps in the manner of suspenders. The garments can be easily disconnected from each other, for the 40 already mentioned purpose of enabling them to be separately worn. Separate belts or straps are not required to secure smooth fitting of the garments, a smooth fit being obtained by the adjustability of the suspender-straps. The garments do not warm portions 45 of the body where warmth is not required, and they do not cause pressure on the abdominal regions, where ordinary underclothing is usually tight.

An embodiment of the present invention 50 is illustrated in the annexed drawing, Figure 1 being a front view showing the abdomen covering alone suspended from the wearer's shoulders; Fig. 2 is a rear view of Fig. 1; Fig. 3 is a similar view to Fig. 2 55 showing a slightly modified form of such abdomen covering; Fig. 4 is a front view

showing the back covering alone on the body; Fig. 5 is a rear view of Fig. 4; Fig. 6 is a front view showing the combined abdomen and back coverings applied to the 60 body, and Fig. 7 is a rear view of Fig. 6.

Referring to Figs. 1 and 2 the abdomen covering *b* is suspended on the body by means of front straps *a* and back straps *h* provided with rows of button holes *b*³ 65 adapted to be attached to buttons *b*² secured to waistbands *b*¹ of the covering so that the height of the latter may be conveniently adjusted. The straps *a* and *h* are secured together by a band *e* passing round the back 70 of the neck as shown in Figs. 2 and 3. Other buttons are provided on the waistband *b*¹ to adjust the garment as to width by connecting the straps *a* and *h* to different buttons.

75 The covering can be fastened at the rear by strings or the like *z* as shown in Fig. 2 or the rear ends *y* thereof may overlap as shown in Fig. 3 and be buttoned together as at *y*¹. In this latter form, sufficient buttons 80 and button holes are provided to allow for adjustment as to width, and it is also desirable to provide an additional back strap *h*¹ secured at opposite ends to the neck strap *e* and to one of the rear ends *y* of the covering 85 and provided with a row of button holes *h*² for use in adjustably suspending the garment according to the adjustment of the main straps *h* as previously explained.

Referring to Figs. 4 and 5 these show in 90 front and rear view the back covering *d* which is a simple garment having arm-holes *i* and somewhat in the form of an ordinary waist-coat but open at the front.

Figs. 6 and 7 show both garments applied 95 to the body the back covering *d* being below and the abdomen covering outermost, said back covering being provided with suitably disposed buttons *d*¹ for attachment with appropriate button holes *d*³ *b*³, in the straps *a* 100 and *h* and band *e* of the abdomen covering.

The bands *a* *h* and *e* enable the abdomen covering *b* of the garment to be worn without any pressure whatever on the abdominal regions, no additional means of attachment being required to hold the garment smoothly against the body. To insure smooth fitting in all cases, the length and width of the garment can be regulated, as before described. This arrangement has the 110 advantage that in making a number of garments the respective parts can all be cut

to one size, and the finished garments can then be adjusted to different sizes on the person. Instead of buttons and button-holes hooks and eyes, studs, buckles and the like 5 can be used, but these serve solely for suspending the garments on the body, and not for tightening or fastening them. Smooth fitting is secured solely by means of the adjustability of the connections.

10 The garments and straps or bands can be made of any suitable material.

What I claim as my invention and desire to secure by Letters Patent of the United States is:—

15 1. An under garment for imparting warmth to certain parts of the body, comprising the combination with a frontal member adapted to cover the abdomen only without pressure, waist-bands on said frontal member and shoulder suspension straps detachably and adjustably secured to said waist-bands, of a back covering member having arm holes, and means for detachable connection of said back covering member 20 with the suspension straps of the frontal 25

member, said two members being capable of wear independently of each other, substantially as set forth.

2. An under garment for imparting warmth to certain parts of the body, comprising the combination of a frontal member adapted to cover the abdomen only without pressure, waist-bands on said frontal member, shoulder suspension straps in connection with said waist-bands, a back covering member having arm-holes and means for detachably and adjustably connecting said back covering member with the shoulder straps of the frontal member whereby the combined garment may be regulated as to 30 height and width, said two members being capable of wear independently of each other, 35 substantially as set forth.

In witness whereof I have signed this specification in the presence of two witnesses. 40 45

AUGUST HOLSTE.
